UNITED STATES PATENT OFFICE.

SYLVESTER C. BROWN, OF MOUNT PLEASANT, MICHIGAN.

WAGON-BOX.

SPECIFICATION forming part of Letters Patent No. 233,655, dated October 26, 1880.

Application filed July 31, 1880. (No model.)

To all whom it may concern:

Be it known that I, SYLVESTER C. BROWN, of Mount Pleasant, Isabella county, Michigan, have invented an Improvement in Wagon-
5 Boxes, of which the following is a specification.

The nature of this invention relates to certain new and useful improvements in wagon-boxes; and the invention consists in the peculiar construction and arrangement of parts, 10 whereby the end-boards retain the several parts in their relative positions, all as more fully hereinafter set forth.

Figure 1 is a perspective view of my improved wagon-box. Figs. 2, 3, 4, 5, and 6 are 15 details of construction.

In the accompanying drawings, which form a part of this specification, A represents the sides, B the end-boards, and C the bolsters, of a wagon-box.

20 At the four corners of the box and to the side-boards A, I properly bolt the female dovetail iron D, designed to receive the ends of the end-boards. The same bolts, a, which secure these irons in place also pass through 25 an iron, E, the lower end of which projects below the bottom of the box and is provided with a T-head, F.

An iron, G, is secured to the under side of each bolster C and near the ends thereof, and 30 through these irons and the bolsters are formed the T-slots a. Between the two irons E upon the side-boards I secure similar irons H, which are likewise provided with the T-heads above described.

35 To each end of the end-boards and upon each side thereof I bolt an iron, I, provided with the dovetail rib b, thus forming upon each end of the end-boards a male dovetail. When it is desired to put this box together. 40 the side-boards are set up, the T-heads of the irons E and H projecting downward through the slots a in the ends of the bolsters C and irons G, when they are pushed outwardly, compelling the heads of their irons to engage 45 with the smaller portion of the slots a. The end-boards are then put in place. The two members of the dovetails coming together

firmly secures the sides in place, from which they cannot be removed without first removing the end-boards. 50

By this construction of parts I produce a strong wagon-box, and one that can be readily set up or knocked down, while I dispense with the various rods and other devices heretofore used for holding the sides in place. 55

I am aware that the end-gate of a wagon-body has heretofore been removably secured to the body by means of female dovetail irons secured to the inner faces of the longitudinal sides of the body, which female irons receive 60 male dovetail irons secured to the ends of the gate and sliding in the female irons, and I therefore lay no claim, broadly, to such construction, my invention being confined to the details of construction pointed out in the 65 claims.

What I claim as my invention is—

1. The combination, with the dovetail female irons D and irons E, with T-heads secured to the side-boards, of the bolsters C and 70 the end-gate B, having the male irons I, substantially as described, and for the purpose set forth.

2. The combination, with the side-boards A, dovetail female irons D, irons E, with T- 75 heads, and bolts a', securing both the irons D and E to the side-boards, of the bolsters C and plates G, both provided with T-shaped slots registering with each other, and the end-gate B, having the male irons I, with dove- 80 tail ribs b, substantially as described, and for the purpose set forth.

3. The combination, with the side-boards A, of the irons H, secured thereto and provided with T-shaped heads, of the bolsters C, 85 having T-shaped slots near their ends, and plates G, with T-shaped slots registering with those in the bolsters and secured thereto, substantially as described, and for the purpose set forth.

SYLVESTER C. BROWN.
